UNITED STATES PATENT OFFICE.

MARVIN H. BABBITT AND JESSE BABBITT, OF ELKHART, INDIANA.

MOUTHPIECE FOR WIND MUSICAL INSTRUMENTS.

1,385,239.

Specification of Letters Patent. Patented July 19, 1921.

Application filed December 11, 1919. Serial No. 344,196.

To all whom it may concern:

Be it known that we, MARVIN H. BABBITT and JESSE BABBITT, citizens of the United States, residing in the city of Elkhart, 5 county of Elkhart, Indiana, have invented certain new and useful Improvements in Mouthpieces for Wind Musical Instruments, of which the following is a specification.

This invention relates to mouthpieces for 10 wind musical instruments, and especially to mouthpieces for saxophones.

It is well known to those experienced in the particular art that almost all saxophone mouthpieces are made of hard rubber and 15 that the molding process is used in the construction thereof, which process requires the use of a removable core in the mold, metal or otherwise, to form the bore of the mouthpiece, said core being usually withdrawn 20 from the mold before the rubber has hardened and while still somewhat elastic. This process of molding saxophone mouthpieces in one piece is necessarily limited to the use of rubber, for, rubber being elastic, the body 25 of the mouthpiece is not materially distorted when the mold core is withdrawn. In any event, the distortion due to the withdrawal of the core is only temporary due to the elasticity of the rubber body of the mouth- 30 piece. As a material for the construction of mouthpieces for musical instruments rubber has its good and bad qualities and is not acceptable to all persons, many of whom accept it because there is nothing better 35 offered.

The object of our invention is the production of a saxophone mouth piece which may be molded from any fusible material which is or may be inelastic while in a semimolten 40 state and after hardening. There are certain special fusible compositions of matter, which resemble hard rubber in appearance, used in the various arts as acceptable substitutes for hard rubber which are desirable 45 material for the construction of saxophone mouthpieces, but the inelastic quality of such materials renders the use thereof for that purpose impossible under the present process of manufacture.

50 The principal object, therefore, of our invention is to make a saxophone mouthpiece in two or more pieces to enable the use of certain special compositions of matter which are inelastic and which resemble hard rubber 55 in appearance, and to some extent in tex-

ture, whereby the mold core can be readily withdrawn without distortion of the mouthpiece body. And while our invention may be used in the manufacture of hard rubber mouthpieces it is not primarily intended for 60 that purpose, although we do not limit the invention to inelastic special compositions used for the manufacture of mouthpieces.

Other objects of our invention are mentioned and described herein.

The preferred embodiment of our invention is illustrated in the accompanying drawing in which Figure 1 is an exterior side view of a saxophone mouthpiece made according to our invention; Fig. 2 is a sectional view taken longitudinally of the member shown in Fig. 1; Fig. 3 is a view of the mouthpiece bushing partially in section; and Fig. 4 is a view showing a modification.

Like numerals of reference indicate like 75 parts throughout the several views on the drawing.

Referring to the drawing in detail the numeral 1 indicates the usual hollow or tubular body member of a mouthpiece for a saxophone 80 which may be made of any suitable material and which is provided with the usual lateral air orifice 2 formed in the lay or face 3, the usual air passage or channel 4 terminating at and communicating with the bushing 85 bore 5 at the point 6 which may be intermediate the inner end 7 of said orifice and the outlet 8 of the body 1. The body bore 5 may be cylindrical in formation and may be slightly greater in diameter than the 90 diameter or transverse dimension of the passage 4 to enable the ready withdrawal of a mold core therethrough.

Numeral 9 indicates a tubular bushing member arranged within the bore 5 and substantially coextensive in length therewith and fitting said bore with the minimum amount of play, the diameter of the bore of which bushing may be substantially less than the diameter of the channel or passage 100 4. The bushing 9 may be flanged at one end thereof which flange may be provided with the annular sloping retaining ring seat 10 which seat is adapted to coöperate with the annular retaining ring seat 11 formed 105 on the end of the body member 1, the slope of the latter seat being opposed to that of the seat 10 and forming in cross-section a ridge shaped structure which is split at its highest point. The numeral 12 indicates 110

an annular ductile metal band or ring arranged around said ridge, in encompassment thereof, and having its edges bent over upon the opposed sloping faces or seats 10 and 5 11 for rigidly retaining the bushing 9 within the bore 5 of the mouthpiece body.

The numerals 13, 13 indicate a plurality of annular grooves or furrows formed in the exterior surface of the bushing body 10 which we preferably coat with shellac, or like substance, before inserting the bushing in the bore 5, which grooves serve to carry the shellac into said bore for distribution thereof where it hardens and forms a seal 15 against the passage of air around the exterior of the bushing body. The inner end of the bore of the bushing 9 may be somewhat tapered or belled at 14 to conform with the contour of the passage 4 of the mouthpiece body. In the modification shown in Fig. 4 we effect a screw thread connection 15 between the bushing 9 and the bore 5 of the body of the mouthpiece for more securely 20 fastening the interior engagement of said 25 members.

We claim:

1. A mouthpiece for wind musical instruments of the class described comprising a tubular body provided with a lateral orifice 30 adjacent one end thereof and a bore at the opposite end thereof; and a separate tubular bushing arranged within said body bore, the forward end of said bushing terminating between the inner end of said lateral orifice 35 and the outer end of said body bore.

2. A mouthpiece for wind musical instruments of the class described comprising a tubular body provided with a lateral orifice adjacent one end thereof and a bore at the 40 opposite end thereof; a separate tubular bushing arranged within said body bore;

and means for fastening said bushing within said body bore.

3. A mouthpiece for wind musical instruments of the class described comprising a 45 tubular body provided with a lateral orifice adjacent one end thereof and a bore at the opposite end thereof; a separate tubular bushing arranged within said body bore; and a fastener element engaging both bushing and body for preventing displacement of said bushing from said bore.

4. A mouthpiece for wind musical instruments of the class described comprising a 50 tubular body provided with a lateral orifice and a bore at the opposite end thereof; a separate tubular bushing arranged within said body bore; and an annular fastener band engaging both said body and bushing to retain said bushing within said bore.

5. A mouthpiece for wind musical instruments of the class described comprising a tubular body provided with a lateral orifice and a bore at the opposite end thereof; a separate tubular bushing arranged within 65 said body bore; and a complementary spiral connection between said bushing and said body bore.

6. A mouthpiece for wind musical instruments of the class described comprising a 70 tubular body provided with a lateral orifice and a bore at the opposite end thereof; a separate tubular bushing arranged within said body bore; and a sealing element between the exterior of said bushing and said 75 body bore to prevent air leakage.

In testimony whereof we have hereunto affixed our signatures this 6th day of December, 1919.

MARVIN H. BABBITT
JESSE BABBITT.
